UNITED STATES PATENT OFFICE.

JACOB JACOBS, OF BROOKLYN, NEW YORK.

DESIGN FOR GLASS OR TILE.

SPECIFICATION forming part of Design No. 27,878, dated November 16, 1897.

Application filed October 9, 1897. Serial No. 654,721. Term of patent 14 years.

To all whom it may concern:

Be it known that I, JACOB JACOBS, of Brooklyn, in the county of Kings, and in the State of New York, have invented a certain new and original Design for Glasses or Tiles; and I do hereby declare that the following is a full, clear, and exact description thereof, reference being had to the accompanying drawings, in which—

10 Figure 1 is a perspective view of a glass or tile embodying my design, and Fig. 2 a plan view thereof.

Letters of like name and kind refer to like parts in each of the figures.

15 The object of my invention is to produce a new and original shape for glasses or tiles; and to this end said invention consists in the design for the glass or tile substantially as herein set forth.

20 The glass or tile A has an outline that in

general shape is rectangular, and at each of the four corners is a flat-sided pointed projection B. On opposite sides of each projection B and forming obtuse angles therewith are straight or plane surfaces C and C, and 25 between said surfaces, at the same side of the glass or tile, the sides of the latter are dished or concave.

Having thus described my invention, what I claim is—

30 The design for a glass or tile, substantially as shown and described.

In testimony that I claim the foregoing I have hereunto set my hand this 30th day of September, 1897.

JACOB JACOBS.
